Gustavus G. Wagner.

Inventor.

UNITED STATES PATENT OFFICE.

GUSTAVUS G. WAGNER, OF MOUNT VERNON, NEW YORK.

RAILWAY-CAR SIGNAL.

SPECIFICATION forming part of Letters Patent No. 302,451, dated July 22, 1884

Application filed November 5, 1883. (No model.)

To all whom it may concern:

Be it known that I, GUSTAVUS G. WAGNER, a citizen of the United States residing at Mount Vernon, in the county of Westchester 5 and State of New York, have invented a new and useful Improvement in Railway-Car Signals, of which the following is a specification.

My invention relates to the class of signals which are displayed in the rear of a train for 10 the purpose of indicating the motion of the train or when the train is standing still. When my signal is applied to a car, it operates as follows: When the car is moving in the direction from the observer, a white disk 15 or light is shown. When the car moves in the direction toward the observer, a red disk or light is shown. When the car is standing still, a red disk or light is shown. When the car is moving slowly in the direction away 20 from the observer, an alternate red and white disk is shown, or, at night a red and white light is flashed. This enables the engineer of the following train to determine the movement of the train ahead of him. I accomplish 25 this by the mechanism illustrated in the accompanying drawings, which are part of this specification.

Figure 1 represents a vertical cross-section. Fig. 2 represents a front elevation of the 30 signal box or lamp. Fig. 3 represents the double-threaded screw-cam on a fraction of a car-axle, and the lower part of the movable frame.

Similar letters refer to similar parts throughout the several views.

To the car-axle *a*, I rigidly fasten the cam, which consists of a double-threaded screw, one end of which ends in the groove *b*, the periphery of which is true with that of the axle *a*, and the flanges *c* and *c'*, the other end of 40 the screw ends in the groove *b'*, the periphery of which is eccentric to that of the axle and the flanges *c* and *c'*.

To the movable frame *d* are rigidly fastened two guide-lips, *e* and *e'*, directly opposite each 45 other and at right angles to the axle, and mesh with the screw-threads *f*. To carry the frame *d* from the circumferential groove *b* to the circumferential groove *b'*, and vice versa, I employ a screw, as shown in Fig. 3, which 50 has two spirals running in the same direction. The object of the double spiral is to have the

grooves always opposite each other and on a line at right angles to the axle. The movable frame *d* is also provided with four guide-arms, *g*, which ride on the periphery of the flanges *c* and *c'*. One end of the connecting-rod *h* is rigidly fastened to the frame *d*. The other end is jointed to the bell-crank lever *i*, which has its fulcrum at the point *j*. The connecting-rod *k* connects the bell-crank lever *i* with the bellows or air-pump *l*. The air-chamber *m*, connects directly with the air-pump *l* by means of the valve *n*. The upper part of the air-chamber is movable vertically, and is provided with a vent, *p*, and a safety-valve, *q*. The arm *o* is rigidly fastened to the upper part of the air-chamber, and engages with the connecting-rod *r*, one end of which is connected to the movable slide *s*, which is arranged and held in position on the inside of the box *B* by means of the guide *t*. The slide *s* is divided into two halves, the lower half being of a different color to that of the upper half. Thus when the slide by its own gravitation drops, one color is shown through the aperture *A* in the box *B*, and when the slide is raised by means of pumping air into the chamber *m* another color is shown. It will be obvious that when glass is used for the slide and a light placed in the box *B* a lamp 75 is produced.

The operation of my invention is as follows: When the axle moves in one direction, and assuming the direction is as shown by the arrow on the wheel, the guide-lips are carried 85 by means of the threads of the screw to the groove *b'*, which is eccentric to the flanges *c* and *c'*, and thus imparts a reciprocating motion to the frame *d* and to the connecting-rod *h*, which imparts it to the bell-crank lever *i*, thence 90 to the connecting-rod *k*, and to the air-pump *l*. The motion continues and the air-chamber is gradually filled and rises, carrying with it the arm *o*, connecting-rod *r*, and the slide *s*, thus showing a different color when the air-chamber is filled, and the motion continues, the surplus air escapes through the valve *q*. When the motion of the axle ceases, the air in the chamber *m* slowly escapes through the vent *p*, and the slide falls gradually back into 95 its normal position. When the axle revolves in the opposite direction to that indicated by 100

the arrow, the guide-lips are carried to the other side of the cam by means of the screw-threads, and to the groove *b*. This groove having a periphery true with that of the flanges 5 *c* *c'* and axle *a*, no reciprocating motion is imparted to the frame *d*, &c.; hence the slide remains in its normal position, showing danger.

Having thus fully described my invention, 10 what I desire to claim as new and secure by Letters Patent is—

1. In a railway-car signal, the combination, with a car-axle, of a cam capable of imparting a reciprocating motion to a rod connected 15 with the piston of an air-pump when said axle is revolving in one direction and capable of holding said connecting-rod stationary when said axle is revolving in the opposite direction, an expanding air-chamber, and a 20 slide, substantially as herein described, and for the purpose specified.

2. In a railway-car signal, the combination, with a car-axle, of a cam consisting of a double-threaded screw terminating in two circumfer- 25 ential grooves, *b* and *b'*, one of which grooves is concentric and the other eccentric to the

axle and the flanges *c* and *c'*, the frame, as *d*, provided with two guide-lips, as *e* and *e'*, adapted to follow the races of the screw, the guide-arms, as *g*, arranged on said frame to 30 ride on the periphery of the flanges *c* and *c'*, a connecting-rod connecting said frame with the piston of an air-pump, an expanding air-chamber, and a slide arranged to be actuated by said air-chamber, the whole to operate 35 substantially as herein described, and for the purpose specified.

3. In a railway-car signal, the combination, with a car-axle having a double-threaded screw-cam, substantially as herein described, 40 of a frame provided with guide-lips adapted to follow the grooves of the screw, means for connecting said frame with an air-pump, an expanding air-chamber, and a slide, as herein shown, the whole to be operated by the rotary 45 motion of the axle, substantially as herein described, and for the purpose specified.

GUSTAVUS G. WAGNER.
